GOLF PRACTICING MACHINE

Curtis R. Wagner, Denver, Colo., assigner, by
mesne assignments, to Golf Unlimited, Inc.,
Denver, Colo., a corporation of Colorado

Application July 23, 1948, Serial No. 40,387

15 Claims. (Cl. 73—379)

1

This invention relates to improvements in golf practicing machines.

Golf players and others who are interested in this game are always desirous of improving their form and testing their ability to play.

It is the object of this invention to produce a machine that can be employed inside of a building, in an amusement resort, or on the club grounds, and which shall be of such construction that a player can hit a ball in the same manner as he would on the actual golf course and which will indicate the strength of the stroke and will also show the angle of hoist and slice.

Another object of the invention is to produce a device of this type that can be readily connected with an indicator board provided with scales that show by numbers the strength of the stroke, the hoist angle and the in and out slice.

A further object of the invention is to produce a device in which the ball, after it has been struck and brought to rest, can be re-set by merely closing a switch, and in which means is also provided to automatically return all the parts to neutral position.

A further object of the invention is to produce a machine that shall be compact, of moderate size, and so designed and constructed that it will stand up against hard usage and resist strong destructive forces.

A further object of the invention is to produce a machine of the type which shall be so designed that the mechanism that measures the strength of the stroke shall not be affected in any material manner by friction.

A still further object is to produce a machine of the type specified in which the strength of the stroke shall be measured by means that do not employ springs for this purpose.

The above and any other objects that may become apparent as this description proceeds are attained by means of the construction and arrangement of parts that will now be described in detail, and for this purpose, reference will be had to the accompanying drawings in which the invention has been illustrated, and in which:

Figure 1 is a top plan view of the machine;
Figure 2 is a side elevation thereof;

Figure 3 is a section taken on line 3—3,
Figure 4;

Figure 4 is a bottom plan view looking upwardly through the plane designated by reference numeral 4;

Figure 5 is a section taken on line 5—5,
Figure 4;

Figure 6 is a section on line 6—6, Figure 4;
Figure 7 is a section taken on line 7—7,

Figure 4;

Figure 8 is a section taken on line 8—8, 60
Figure 4;

2

Figure 9 is a fragmentary section taken on line 9—9, Figure 8; and

Figure 10 is a fragmentary section taken on line 10—10, Figure 8.

5 Referring now to the drawing, reference numeral 15 designates a base on which the machine rests and to which it is attached by means of bolts 16 as indicated in Figures 5, 6 and 7. The machine consists of an elongated housing having 10 sides 17, ends 18 and a top 19. The top has a depressed area like that designated by reference numeral 20, and is provided with a central elongated opening 21. Ends 18 are provided on their inner surfaces with lugs 22 for the reception of bolts 16. Positioned within the housing is the operating mechanism which will now be described in detail.

Reference numeral 23 designates the side members of a rectangular frame. One end of 20 members 23 are connected by means of a bar 24, and the other ends are connected by bar 25. The rectangular frame that has just been described has trunnions 26 that extend outwardly from the side members and are 25 mounted for rotation in bearings 27 positioned on the inner surface of sides 17. It will be observed that the trunnions are positioned nearer the lefthand end of the frame than the righthand end when viewed as in Figure 4. Positioned on the inside of the rectangular frame that has just been described is a second rectangular frame comprising side members 28 and ends 29 that are provided with trunnions 30 and 31, the former being mounted for rotation in a ball bearing 33 in bar 24 and the latter in a similar bearing in bar 25, as shown in Figure 3. Trunnion 30 terminates in a block 32 and trunnion 31 projects forwardly as shown in Figure 3 and has a brake drum 34 with which 30 a brake band 35 cooperates. The brake band is forced against the drum by means of springs 36 as shown in Figure 4 and is held against rotation by means of an arm 37. A counterweight 38 is attached to the forward end of trunnion 31 and can be moved longitudinally 45 so as to assist in balancing the frame comprising members 23. Attached to the block 32 is a member terminating in a rearwardly opening V-groove 39 whose function will appear presently.

50 Referring now more particularly to Figures 3 and 4, it will be observed that two short angle iron brackets 40 and 41 are secured to the top of the housing by means of suitable bolts 42. The vertical side of each bracket has two pair 55 of inwardly projecting pins 43 forming guides for plate 44. This plate has a pair of spaced lugs 45 to which connecting rod 46 is pivotally connected. The other end of the connecting rod is pivoted at 47 to the end of a crank arm 48 that is fastened to shaft 49. Shaft 49 is mounted in bearings in the ends of brackets 50.

Attached to shaft 49, at the lefthand end thereof when viewed as in Figure 8, is a gear segment 51 that is in mesh with pinion 52 on the end of shaft 53 of the selsyn motor 54. A switch 55 is secured to the inner surface of side 17 by means of a bracket 56. Switch 55 has a spring contact 57 that is engaged by arm 58 on gear segment 51 for a purpose that will hereinafter appear. Shaft 49 is provided with a crank arm 59 (Fig. 9) whose end is connected at 60 with the outer end of piston rod 61 that is connected with a piston in hydraulic cylinder 62 that is pivotally connected with wall 18 by lugs 63. Cylinder 62 is part of a hydraulic dash pot or brake whose function will appear later. A third crank arm 64 (Figure 9) is attached to shaft 49 near its top when viewed as in Figure 4. A bracket 65 has its upper end secured to the under surface of top 19. A lever 66 is connected at a point 67 near its center, to bracket 65 and has one end connected to the end of crank arm 64 by means of a connecting rod 68 as shown most clearly in Figure 9. A push bar 69 has its lower end pivoted to lever 66 at 70 and extends through an opening in top 19 terminating in an enlarged head 71. The player exerting pressure on head 71, with his foot, rocks lever 66 about its pivot 67 and turns shaft 49 through a small angle, in a counter-clockwise direction, when viewed as in Figure 9 and in a clockwise direction when viewed as in Figure 10. When shaft 49 is turned by the downward movement of push bar 69, piston rod 61 will be pulled outwardly from cylinder 62 by the action of crank arm 59 and gear segment 51 (Fig. 10) turned through a corresponding angle. Spring 72 that connects pivot 47 with end wall 18 (Fig. 4) is under tension and is further tensioned when shaft 49 is turned by the downward movement of the push bar and exerts a sufficient torque force on shaft 49 to return it and the parts attached thereto to the position shown in Figure 9 when the pressure on 71 is removed. Referring now to Figure 3, it will be observed that when shaft 49 and crank arm 48 are turned in a clockwise direction, connecting rod 46 moves plate 44 towards the left into the V-groove 39 in the member attached to block 33 on trunnion 30, thereby bringing the V-groove into parallel relation with itself and frame 28, 29 into horizontal position. The movement of plate 44 into the V-groove also serves to bring the frame that tilts on trunnions 26 into horizontal position. A downward pressure on bush bar 69 therefore brings the two frames into operative position for another play. Friction brake 34, 35 serves to hold the smaller frame from accidental rotation about its trunnions and a friction device comprising a friction head 73 carried by bracket 74 (Figures 4, 7 and 9) and urged against the inner surface of bar 23 by spring 75 serves to hold the larger frame from accidental movement about trunnions 26 after it has been reset by the action of plate 44.

Attached to or carried by the lower end of bracket 65 is a normally open switch comprising contacts 76 and 77, the latter is positioned in line with push bar 69 which engages it in its downward movement and closes an electric circuit to a counting device which records the number of hits.

Shaft 78 is journaled in suitable bearings in frame members 28 (Figure 6) and carries an arm 79 to the outer end of which a golf ball 80 or a rubber ball of the same size and shape

as a golf ball is attached by suitable means. A selsyn motor 81 is attached to shaft 78 and serves to bring arm 79 and ball 80 into the position shown in Figure 3 whenever the parts are reset by the downward movement of the plunger pedal which, as above explained, turns selsyn motor 54 that is operatively connected with motor 81. Member 82 is a counteweight compensating for the weight of motor 81. A one-way ratchet device between shaft 78 and motor 81 permits the shaft to turn freely in response to a hit by a golf club.

The force of the hit, which is a measure of the distance the ball would travel, is measured by the number of times shaft 78 and arm 79 with ball 80 attached thereto rotates. After being hit the ball and shaft rotate very fast and it is necessary to provide a mechanism for counting and registering the number of turns the shaft makes.

Bars 28 are provided with oppositely positioned openings 84 between which ball 80 moves once in each turn about shaft 78. An incandescent lamp 85 is positioned in a small housing on the outside of one of the frame members 28 so as to direct a beam of light into the corresponding opening in the opposite frame member, a photo cell 86 is secured to the outside of the opposite frame member 28 in position to receive light from lamp 85. The light from lamp 85 will be interrupted each time ball 80 passes between holes 84. A suitable counting mechanism is operated by current from the photo cell. The counting mechanism has not been illustrated in detail as it is very intricate but may be considered as being a pointer moving over a scale with a step by step motion imparted to it by a magnet energized from the photo cell.

The distance that a ball will travel is not only directly proportional to the force of the impact with the club, but is also dependent on the angle that the component of the force makes with a horizontal plane. In the machine illustrated in the drawings the larger frame is connected with the base by pivots 26, that are spaced from the axis of shaft 78. As shown in Figure 4, the two axes are in the same horizontal plane but in different vertical planes. If the impact force is exerted in a direction parallel with the common axial plane of the trunnions and of shaft 78, there will be no tendency to turn the frames about the axis of their trunnions, but if the force is directed upwardly or downwardly relative to such a plane, the larger frame will turn about its trunnion axis. The angular movement of the large frame about its trunnion axis is a measure reflecting the value and the direction of the force. Means has been provided for indicating the vertical angular movement of the large frame which means will now be described by reference to Figures 3 and 4.

From Figure 3 it will be seen that a rigid bar 87 projects from one of the side members 23 of the larger frame. A switch arm 88 is pivoted at 89 for movement over a number of contacts 90 arranged in an arc concentric with pivot 89. A link 91 connects the end of bar 87 with a short arm fixed to the switch arm and therefore, whenever the large frame turns about its trunnions the angular extent of such movement will be indicated by the position of the switch arm. The vertical position of the switch arm 88 represents the horizontal position of the large frame. The position of the switch arm is shown on a suitable indicator by means of a series of lamps con-

nected with the switch in the manner shown in Figure 3, the lamps being numbered in order from the center as shown.

The amount of in or out slice, or, in other words, the angle of the impact force relative to a vertical plane passing through trunnions 30 and 31 which tends to turn the small frame about its trunnion axis is indicated by a switch similar to the one just described which is illustrated in Figure 5. Referring now to Figure 5, it will be seen that a rigid arm or bar 92 is attached at one end to trunnion 31 and extends laterally, a switch comprising a switch arm 88a is pivoted to frame member 25 for movement over the arcuate row of contacts 90a. The end of bar 92 is connected with the lateral arm of the pivoted switch arm by a link 91a. Switch arm 88a and contacts 90a are connected with indicator lamps in the manner shown in Figure 3.

Operation

The machine illustrated in the drawings and above described is positioned on a horizontal base 15 and the parts are brought into operative or set position by exerting a downward pressure on head 71 of push bar 69 in the manner above explained. Ball 80 is now in the position shown in Figure 3. The player hits the ball on the right side, when viewed as in Figure 3. The impact of the club sets ball 80, arm 79 and shaft 78 turning. Each time the ball passes between the lamp and the photo cell, it interrupts the light beam, thereby operating the counter. In Figure 7, the counter has been indicated by a rectangle as its specific construction constitutes a separate invention. The number of complete turns that the ball makes is an approximate measure of the impact force and serves to compare the forces of separate strokes. If the direction of the impact force is parallel with a plane containing the axis of shaft 78 and the axis of trunnions 26, the tendency to turn the frames about trunnions 26 is a minimum, being due solely to the torque due to the lateral displacement of the ball and the force from the plane of the trunnion pivots. If the direction of the impact force is inclined upwardly or downwardly from the horizontal, the frames will tip about trunnions 26 and the angle indicated by lamps as illustrated in Figure 3. If the direction of the impact force angles with respect to a vertical plane that is perpendicular to the axes of trunnions 26, such a force will have a component that will move ball 80 to either side of the vertical when viewed as in Figure 6 and the value of such lateral force is indicated by the switch shown in Figure 5.

After each stroke the parts are returned to "set" position by a downward movement of push bar 69.

In the drawing a specific structure has been shown. It is evident that changes may be made in some of the elements and it is to be understood that applicant reserves the right to substitute for any one of the elements a mechanically equivalent element, all within the scope of the appended claims.

What is claimed as new is:

1. A golf game practicing device of the type comprising a base, a gimbal, the outer frame of the gimbal having trunnions journaled in the base, the inner frame of the gimbal being journaled in the outer frame for rocking movement about an axis perpendicular to the trunnion axis of the outer frame, a shaft journaled in the inner frame for rotation about an axis parallel with the

trunnion axis of the outer frame, an arm projecting radially from the shaft, positioned in the inner frame, a ball attached to the outer end of the arm, the axis of the shaft being displaced from the trunnion axis of the outer frame in the direction of the axis of the trunnions of the inner frame, whereby impact forces applied to the ball in directions displaced from the horizontal will rock the outer frame about its trunnions and components of said forces angularly displaced from a vertical plane perpendicular to the axis of the shaft will rock the inner frame about its trunnions, means comprising electrically operated indicators associated with the frames for visually indicating the extent of their angular displacement due to impact, means for registering the number of turns of the shaft due to each impact blow, means for returning the two frames to normal position after each operation, and electromagnetic means for returning the shaft and arm to normal position after each operation.

2. A golf game practicing device comprising a base, a gimbal comprising an inner and an outer frame mounted on the base, the outer frame having aligned trunnions journaled in the base, the inner frame having aligned trunnions journaled in the outer frame for rocking movement on an axis perpendicular to the trunnion axis of the outer frame, a shaft journaled in the inner frame for rotation about a horizontal axis parallel with the trunnion axis of the outer frame, an arm projecting radially from the shaft at a point within the inner frame and a ball secured to the end of the arm, the ball being normally positioned above the frame in position to be hit by a golf club, the ball and shaft being rotatable in response to the impact force, means for registering the number of turns made by the shaft and ball in response to each impact, thereby measuring the force thereof, means comprising the outer frame and an indicating device connected therewith for measuring the vertical component of the impact force, means comprising the inner frame and an indicating device connected therewith for measuring the horizontal component of the impact force, and means comprising an electric motor means connected with the shaft for moving the ball into operative position after it has spent the energy imparted to it by the impact force.

3. A golf game practicing device comprising in combination, an oblong base of inverted pan form whose upper wall has an elongated opening, a substantially rectangular gimbal comprising an outer and an inner frame the outer frame being mounted for tilting movement about transversely extending pivots, the inner frame being positioned within the outer frame and mounted thereon for pivotal movement about an axis perpendicular to the pivotal axis of the outer frame, the two frames being movable relative to the base, the inner frame having a transverse shaft pivoted in its side members for rotation on an axis parallel with the trunnion axis of the outer frame, an arm extending radially from the shaft, between the sides of the smaller frame, a ball attached to the end of the radial arm, the ball, when in operative position, being positioned above the top of the base, the arm and ball rotating in a plane parallel with the elongated opening in the base means responsive to the tilting of the outer frame for measuring and indicating the angular value of said tilt, means responsive to the tilting of the inner frame relative to the outer frame for indicating the angular value of said last named tilt, means comprising a photo cell, a lamp and an

electronic counter for counting the number of times the shaft and ball turn in response to an impact force, means for moving the two frames of the gimbal to normal horizontal position comprising a member having angularly related flat surfaces connected with one of the trunnions of the inner frame, said surfaces being oppositely inclined to the axes of the trunnions, a horizontal plate slideably connected with the base for engagement with one of said surfaces, and means comprising a push bar accessible from the outside of the base for reciprocating said plate.

4. A device in accordance with claim 3 in which each of the pivoted frames has operatively associated therewith a friction device for holding them in adjusted position.

5. A device in accordance with claim 3 in which an electromagnetic counter mechanism is provided for counting the number of times the frame and ball are reset.

6. A golf-game practicing machine comprising, in combination, an oblong inverted pan-like base having its top provided with a longitudinally extending elongated opening, a gimbal comprising two oblong frames of different sizes, the smaller being positioned in the larger, the outer of which is pivoted to the sides of the base and the inner of which is positioned within the outer and pivoted to the ends of the larger frame, a shaft journaled in the sides of the inner frame, an arm extending radially from the shaft, a ball secured to the end of the arm, the arm being of such length that it will extend through said opening and the ball will be positioned wholly above the base when the arm is in upright position, the ball, arm and shaft being rotatable in response to an impact force, means comprising a lamp positioned on one side of the path of the ball, a photo cell positioned on the other side of the path and an electric counter for counting the number of times the ball passes between the lamp and the photo cell in response to an impact force, and an electromagnetic device, for returning the ball to operative position with the ball above the base.

7. A device in accordance with claim 6 in which means is provided for measuring the angle of tilt of the outer frame relative to the base, and means for measuring the angle of tilt of the inner frame relative to the outer.

8. A device in accordance with claim 6 in which means is provided for simultaneously moving the two frames into coplanar relation and for moving the outer frame into a position parallel with the base.

9. A device in accordance with claim 6 in which a friction element secured to the base is in engagement with the outer frame and a friction element carried by the outer frame is in engagement with the inner frame to resist accidental movement of said frames about their pivots.

10. A device in accordance with claim 6 in which each frame of the gimbal has a counter-weight adjustably connected therewith.

11. A golf practicing apparatus comprising, in combination, a base, a gimbal comprising an outer and an inner frame, the outer frame having trunnions journaled on the base, the inner frame having trunnions journaled in the outer frame for rocking movement about an axis perpendicular to the trunnions on the outer frame, a shaft journaled in the inner frame for rotation about an axis parallel with the trunnion axis of the outer frame, said shaft having a radial arm having a ball attached to its end, the shaft and

arm being mounted to turn when the ball is hit, means for counting the number of turns made by the shaft in response to said impact, means comprising the outer gimbal frame for gauging the vertical impact angle, above and below a horizontal plane, means comprising the inner gimbal frame for gauging the lateral impact angle with respect to a vertical plane perpendicular to the shaft, and electromagnetic means for resetting the ball in operative position after each operation.

12. A device in accordance with claim 11 in which means is provided for simultaneously moving the two frames into coplanar relation and for moving the outer frame into a position parallel with the base.

13. A device in accordance with claim 11 in which a friction element secured to the base is in engagement with the outer frame and a friction element carried by the outer frame is in engagement with the inner frame to resist accidental movement of said frames about their pivots.

14. A device in accordance with claim 11 in which each frame of the gimbal has a counter-weight adjustably connected therewith.

15. A golf practicing apparatus comprising, in combination, a base, a gimbal comprising an outer and an inner frame, the outer frame having trunnions journaled on the base, the inner frame having trunnions journaled in the outer frame for rocking movement about an axis perpendicular to the trunnions on the outer frame, a shaft journaled in the inner frame for rotation about an axis parallel with the trunnion axis of the outer frame, said shaft having a radial arm having a ball attached to its end, the shaft and arm being mounted to turn when the ball is hit, means for counting the number of turns made by the shaft in response to said impact, means comprising the outer gimbal frame for gauging the vertical impact angle above and below a horizontal plane, means comprising the inner gimbal frame for gauging the lateral impact angle with respect to a vertical plane perpendicular to the shaft, electromagnetic means for resetting the ball in operative position after each operation, a switch mechanism operatively connected with each gimbal frame, each switch mechanism having a pivoted switch arm, means operatively connecting the arms with their respective frames for commensurate angular movement, a plurality of switch contacts associated with each arm over which the arms move and an electrically operable indicator connected with each set of switch contacts for visually indicating the angular movements of the frames about their trunnions, when the ball is hit.
